UNITED STATES PATENT OFFICE.

WILLIAM A. HICKS, OF CINCINNATI, OHIO.

CLOCK.

Application filed May 10, 1921. Serial No. 468,311.

To all whom it may concern:

Be it known that I, WILLIAM A. HICKS, a citizen of the United States, residing at Cincinnati, in the county of Hamilton and 5 State of Ohio, have invented certain new and useful Improvements in Clocks, of which the following is a specification.

My invention relates to clocks and the like, and its object is to simplify the clock 10 mechanism. A further object is to drive the clock by the aid of electricity, avoiding winding, but without loss or gain due to variations in strength of the electric current. Other objects will appear in the course 15 of the ensuing description.

I attain these objects by the apparatus illustrated, for example, in the accompanying drawing, in which—

Figure 1 is a front elevation of a clock 20 embodying my invention, part of the front and dial thereof being omitted to reveal the interior mechanism, and the electrical connections being shown in diagram;

Fig. 2 is a vertical section on a plane corresponding to the line 2—2 of Fig. 1, but showing the permanent magnet and its mounting in end elevation, the view being toward the right in Fig. 1; and

Fig. 3 is a partial view corresponding to 30 Fig. 1, but showing the parts of the mechanism in different operating positions.

The clock casing 1, of any usual design, with the transparent closure 2 in front, has the dial 3 visible through this closure, with 35 the usual markings thereon. The frame 4 for the clock mechanism or movement comprises, as here shown, the front standard 5, middle standard 6, and rear standard 7, all fixed to the base 8, which latter is fixed 40 to the bottom 9 of the casing 1. The dial 3 may be fixed to the casing front 10, or to the front of the frame 4, or to both parts as here-in shown. Also, the frame 4 may be fixed to the bottom 9, or to the back 11 of the 45 casing, or to both, as here shown. These are details that may vary as they do in various kinds of clocks constructed and operated as heretofore.

The minute hand 12 is mounted in a usual 50 manner on the front end part of the arbor 13, to turn therewith; and the hour hand 14 is frictionally mounted on the sleeve 15, to turn with the sleeve. This sleeve surrounds the arbor 13 and is journaled in the 55 upper end part of the front standard 5, extending out of the rear thereof and having

fixed on it the hour wheel 16. The minute-hand arbor 13 extends out of the rear end of the hour-hand sleeve 15, and has fixed on it the minute wheel 17. Thus, these 60 wheels and the respective hands are coaxial, much in the same manner as with usual clocks or watches.

The balance wheel 18 is fixed on a shaft 19 having a rear spindle 20 bearing in the 65 upper part of the rear standard 7, with the wheel 18 close to this bearing part and a considerable distance back from the middle standard 6, in the upper part of which the shaft 19 has a front spindle 21 journaled. 70 This front spindle extends out of the front of the middle standard 6, and has fixed on its extension a disk 22 with an eccentrically located pin 23 extending forward from its flat front face. These parts are preferably 75 concentric with the hands and their wheels, but are distinct therefrom and are not essentially so related to those parts.

On the front side of the middle standard 6 the lever 24 has a fulcrum 25, and the 80 upper end of this lever 24 carries a fork 26 close to the front face of the disk 22 and so proportioned and related thereto that this fork 26 will receive the pin 23 between its members when this pin is traveling 85 through the lower half of its circle of movement, but will leave the pin 23 free of the fork in the upper half thereof. The upper ends of the fork members are slanted downward and inward to guidingly receive this 90 pin on its entrance to the fork in either direction. The lower end part of the lever 24 carries the forwardly projected stud 27, on which is hung the pawl 28. As here shown, the fork 26 is about twice as far up 95 from the fulcrum 25 as the pawl 28 is down therefrom; so that the pawl moves about half as far as the fork in a given oscillation of the lever 24.

Both the hour wheel 16 and the minute 100 wheel 17 have ratchet teeth entirely around their respective peripheries; and the pawl 28 lies across both peripheries. But the hour wheel 16 is of a diameter such that when the pawl 28 engages on any one of a 105 majority of the teeth in the minute wheel 17 it is prevented from entering any notch of the hour wheel; and one-twelfth of the notches between the minute-wheel teeth, at uniform intervals therearound, are made 110 deep enough for the pawl to enter an adjacent notch between hour-wheel teeth. As

preferred, each wheel has one hundred and eighty teeth, all of the same depth on the hour wheel, but every fifteenth tooth 29 on the minute wheel having the adjacent notch 30 deepened as just noted. The pawl 28 has a counterweight 30 holding the pawl against the minute wheel teeth at all times, and causing it to readily force its way into the deeper notches and against the hour-wheel tooth, whenever such a deeper notch receives the pawl. It will be seen, therefore, that in eleven out of twelve oscillations of the lever 24, the pawl can move only the minute wheel 17; but in every twelfth oscillation it can move both wheels 16 and 17. Thus the hour wheel 16 and hour hand 14 are turned one-twelfth as fast as the minute wheel 17 and minute hand 12, by a regularly repeated oscillation of the lever 24. Clicks 31 and 32 bear lightly on the teeth of the wheels 16 and 17, respectively, to prevent their backward movement; although these may be dispensed with, and the mere inertia or friction in the bearings of these wheels relied upon for this purpose. Also, as here shown, the lever 24 is hung slightly to the right of the vertical line through the center of the disk 22, so that the pawl assumes its advanced position by gravity, and is so held therein while the pin 23 is out of the fork 26; the lever and pawl being held back at the other end of the oscillation, while the pin is out of the fork, by engagement of the pawl with the ratchet wheel. This makes the clicks desirable, as affording a certain stoppage of the wheels, pawl and lever at this stage of the operation.

The frame 4 comprises a left-hand extension 33 near its bottom, from the middle standard 6 to the rear standard 7, under the balance wheel 18, and having a lug 34 upstanding just in front of this wheel 18, and an upstanding lug 35 at the front, about even with the middle standard 6 (Fig. 2). Also, slightly more than half-way back from the flange 35 to the lug 34 this extension has a plate 36 upright thereon.

A flat spring 37 has its lower end part fixed to the top of the extension 33 under the plate 36, where the latter joins this extension; and this spring 37 extends to the right-hand part of the clock casing, then curves upward and to the left, and has its upper end part some distance up, under the shaft 19. This part has fixed on its top a clip with an eccentric pin 38 mounted from front to rear therein, and held against rotation therein by a binding nut 39. The lower end of a thin flexible cord or cable 40 is fixed in this eccentric pin 38; and the upper end of this cord 40 is fixed in the shaft 19. Preferably these cord ends are fixed by passage through holes in the respective pin or shaft, and a knot in the projecting end part of the cord; the edges of

the holes being rounded to avoid cutting the cord. The eccentric pin 38 is for adjusting the length of the cord connection with the shaft 19, by winding more or less of the cord on the pin 38 while the nut 39 is loosened, after which the nut is made tight. Close to the attachment of the lower end of the spring 37 to the extension 33, an adjusting nut 41 has a neck up through the spring with a collar 42 thereabove; and this nut screws up or down on a stud 43 fixed in the bottom 9 of the casing. Thus, screwing this nut up or down will raise or lower the spring 37, as a whole; so that with a given length of cord connection with the shaft 19, this spring will have its tension decreased or increased. Shortening the cord connection will increase the tension; so that either adjustment, or both, may be used to vary the pulling effect of the spring on the cord 40.

A permanent magnet 44, of elongated "horse-shoe" shape, has its heel to the left, and its members straddling the upstanding plate 36, with the free ends or poles 45 upturned slightly, about vertically under the shaft 19 and the cord connection; and an armature 46 is fixed on the lower end part of the spring 37, facing down toward the poles 45. This magnet 44 has forwardly and rearwardly extending trunnions 47 journaled in the lug 35 and lug 34, respectively, of the extension 33; and the latter has an adjusting screw 48 up through it under one member of the magnet, to be engaged by said member and limit the upward swinging of the pole end of the magnet to the desired degree. The heel of the magnet overbalances the pole end; so that the pole end is normally in its highest position as allowed by this screw 48. On this heel is mounted an armature 49, attracted by a temporary electro-magnet 50 fixed thereabove on the left-hand side of the clock casing (Fig. 1) with the axis of the magnet upright. When this electro-magnet is energized, it raises the heel and depresses the poles of the permanent magnet; but on cessation of current in its coils, it allows the magnet 44 to drop back to normal position.

The upstanding plate 36 has on its front side horizontal guide lugs 51 and a guide pin 52. The switch-plate 53 has a horizontal slot receiving the pin 52, and a horizontal shank 54 guided between the lugs 51. The right-hand end of this plate 53 has an upper part 55 inclined down to the left, and a lower hooked part 56 opposite to and about parallel therewith. The plate 36 also has a vertical slot 57 near this end of the switch-plate 53; and a link 58, pivoted to the free upper end part of the spring 37, depends therefrom, with a pin 59 extending forward through and guided in the slot 57 to engage with the inclined parts

55 and 56 of the plate 53, alternately. The left-hand end of the switch-plate 53 has fixed on it the resilient switch-blade 60, extending up and bending to the right; and 5 the top of the plate 36 has the contact piece 61 fixed on it, to be contacted by the blade 60 when the switch-plate is in its right-hand position, but disconnected therefrom, electrically, when the plate is in its 10 left-hand position. These electrically-connecting parts 60 and 61 are suitably insulated from the other parts, as will be understood; and they serve, when connected, to complete a circuit through the electro-magnet 50 and battery 62 by suitable conductors 63, 64 and 65 as seen in the diagram in Fig. 1. It will be understood that the battery 62, in the diagram, represents any suitable source of electrical current, as a dry- 20 battery, storage-battery, dynamo or transformer system, or any device to supply a low-voltage comparatively small current sufficient to supply the friction and inertia losses in the operation of the clock, as will 25 now be described.

Operation: It has been noted that regular oscillation of the lever 24 will cause rotation of the hour and minute hands by means of the pawl and ratchet wheels; the hour hand 30 being advanced one interval at every twelfth oscillation, and the minute hand advanced one interval at every oscillation, of the lever 24.

The spring 37, connected to the shaft 19, 35 limits the shaft 19 and attached balance wheel 18 to oscillations, each having its terminations at the extremes of winding of the cord 40 on the shaft 19 in opposite directions; and the amount of this winding, the 40 speed of oscillation, and, as a resultant of these two factors, the total time of oscillation, depending upon the pull of the spring 37 against the momentum of the balance wheel 18, and the pull of the permanent 45 magnet 44 to assist the spring, which, in turn, with a given magnet 44, will depend upon the degree of recession and approach of the upper end of the spring 37 from and to the magnet poles and of the latter from 50 and to the end of the spring. All of these factors once being fixed in their respective values, the shaft 19 will continue to oscillate at a constant rate. At each twelfth oscillation of the lever 24, the slight additional power to move both wheels and hands 55 will slacken this oscillation during that movement; but in the aggregate, each of these overloads being the same, the rate of operation will be constant. With the adjustments made in conjunction with observations of the rate of running, and comparisons with a correct time-piece, as in regulating any clock or watch, the clock will be 60 adapted to measure and indicate correct time 65 without winding. It is of course necessary

to keep the battery or other current up to such a strength as will move the permanent magnet each time, as is required.

Were this electric current used directly, as by having the electro-magnet to assist the spring 37 directly, it would be necessary 70 to have the strength of the electric current constant, which is impracticable; especially with such a source as a dry-battery, for instance. The permanent magnet will attract always with substantially the same strength, subject only to magnetic disturbances in the earth's field, or molecular changes, and the like, which may be neglected for most practical purposes; especially 80 as these tend to right themselves periodically.

Also, were the electro-magnet 50 permitted to withdraw the permanent magnet 44 from the spring 37 during any substantial 85 part of the period of movement of the spring 37 up or down, the pull of the permanent magnet 44 would then be merely a connection from the spring, and therefore 90 from the balance-wheel shaft 19, to the electro-magnet 50; and the assistance to the spring would partake materially of the variable nature of the electro-magnetic action, incident to the current-strength variation. I provide for the withdrawal of the magnet 95 44 while the spring 37 and connected cord 40 are practically stationary, as the cord connection to the shaft 19 passes its lowest point; and I restore the magnet 44 to its raised position after the spring 37 has gone 100 up away from the magnet 44 far enough to be practically out of the influence of the magnet 44. Thus, the spring does not receive any impetus from the electro-magnetic action, to a material degree, on withdrawal; and it is not materially retarded in its upward movement, by electro-magnetic action, when the magnet 44 is restored. Whatever 105 slight retardation occurs then, is through the practically constant permanent magnetism by the counterweight of the magnet heel, 110 also a constant factor.

The escape of the pin 23 from the fork 26 during one-half of each oscillation gives the effect of oscillating the lever 24 once and 115 advancing either one or both hands, as the case may be, only one tooth space, for each two oscillations of the balance wheel 18. Thus, either excessive diameters for the ratchet wheels 16 and 17, or excessive fineness of their teeth, is avoided; since the wheels need only half as many teeth for a given practical rate of balance-wheel oscillation. With one hundred and eighty teeth, the period of a complete balance-wheel oscillation, or about one complete revolution in each direction, will be twenty seconds; and this is obtainable with such motive and adjusting mechanism as is herein disclosed. The strength and tension of the spring 37 120 125 130

should be so adjusted relative to the mass of the balance-wheel, and the assisting action of the magnet 44 so adjusted, that the proper period of oscillation will be obtained with slightly less than a complete revolution in each direction at each oscillation; although, since the cord 40 can wind more than once around the shaft 19 in either direction, the half-oscillation in either direction can be more than one revolution, should this be desirable or necessary.

Supposing the parts as in Fig. 1, the lever 24 has reached the left-hand end of its lower-end swing, completing a one-tooth advance; and the pin 23 is just leaving the fork 26 to begin its upper ineffective travel. It will go up about ninety degrees, whereupon the spring 37, supposing the parts adjusted for this, will overcome the momentum, the balance-wheel will reverse, and the pin 23 will then descend through this angle, again engaging in the fork 26. It will now swing the lower end of the lever 24 to the right, until it has traveled throughout its lower half-circle of effective operation, leaving the fork 26 upwardly again, at the opposite side, and leaving the pawl 28 in mesh with a succeeding tooth of the minute wheel 17, as seen in Fig. 3. If this tooth should be one of the deep ones, the pawl will also have engaged the coinciding tooth of the hour wheel 16. The pin 23 will now be carried up about ninety degrees on this side, to about its position in Fig. 3, without acting on the lever 24. Then reversal will occur again, the pin will come down through this angle, and will then engage in the fork 26 and swing the lower end of the lever 24 to the left, so that the pawl 28 will advance one or both wheels, as the case may be, one tooth space, during the swing of the pin 23 back through its lower half circle of effective operation.

The permanent magnet 44 has its poles up, in Fig. 1; the switch-plate 53 being to the left and the circuit being broken. As the spring 37 reaches its lowest point and the cord 40 is traveling under the shaft 19, as seen in Fig. 3, the pin 59 engages the lower incline 56, pushing the switch-plate 53 to the right, closing the circuit and energizing the electro-magnet 50, which will quickly withdraw the permanent magnet 44 to the position of Fig. 3, while the spring 37 is practically stationary. Then after the spring 37 has gone up some distance, sufficient to practically nullify the magnetic pull thereon by the upcoming magnet 44, the pin 59 engages the upper incline 55, again pushing the switch-plate to the left and breaking the circuit, upon which gravity restores the magnet 44 to its raised position. The assisting action of this magnet on the spring 37 occurs in the latter part of the descent of the spring 37, after its

armature 46 is very close to the magnet poles 45 but before the magnet-withdrawing circuit closure is effected. The just described operation will be repeated regularly; and the exact strength of the electric current, as affecting the quickness of withdrawal of the magnet 44 during the practically stationary condition of the spring 37 and cord 40, will be negligible, so long as the action is such as to effect this withdrawal well within the period of this condition. The electro-magnetic action is so quick that even a large percentage of variation therein will be small relatively to the period referred to. For instance, with a twenty second period of oscillation, once each way, one second would be required for the cord 40 to pass through its lowest approximately thirty degrees of travel, wherein its effectiveness is very slight; but the loss in quickness of electro-magnetic action, down to any effective current strength, will be but an extremely slight fraction of a second.

Modifications will occur under different conditions, or as may be desirable, and therefore I do not wish to be understood as being limited to this specific disclosure, but what I claim is:

1. In combination with a movable time-indicating element, an oscillating element, a spring moving said oscillating element, means whereby said oscillating element moves said time-indicating element, a permanent magnet, and means whereby said permanent magnet causes movement of said spring.

2. In combination with a movable time-indicating element, an oscillating element, a spring moving said oscillating element, means whereby said oscillating element moves said time-indicating element, an electric-current source, a permanent magnet, and means whereby electric current from said source, acting through the medium of said permanent magnet, causes movement of said spring.

3. In combination with a movable time-indicating element, an oscillating element, means whereby said oscillating element moves said time-indicating element during a part only of its oscillation, a permanent magnet, and means whereby said permanent magnet moves said oscillating element during a period substantially coextensive with the period of movement of said time-indicating element by said oscillating element.

4. In combination with a movable time-indicating element, an oscillating element, means whereby said oscillating element moves said time-indicating element during a part only of its oscillation, an electric-current source, a permanent magnet, and means whereby electric current from said source, acting through the medium of said permanent magnet, moves said oscillating

element during a period substantially coextensive with the period of movement of said time-indicating element by said oscillating element.

5. In combination with a movable time-indicating element, an oscillating element, means whereby said oscillating element moves said time-indicating element, a spring alternately moved by and moving said oscillating element and having a period of substantial rest, and comprising a magnetic part, a permanent magnet having a movement to and from a position in which it can appreciably attract said magnetic part, 70 means having an action to move said permanent magnet from said position during said period of rest, means to return said permanent magnet to said position when said action is stopped, and means actuated by said spring for starting and stopping said action respectively during and after said period of rest.

6. In combination with a movable time-indicating element, an oscillating element, 25 means whereby said oscillating element moves said time-indicating element, a spring alternately moved by and moving said oscillating element and having a period of substantial rest, and comprising a magnetic part, 30 a permanent magnet swinging up and down from a position in which it can appreciably attract said magnetic part, a weight to swing said permanent magnet up, an electromagnet to swing said permanent magnet down, an electric-current source, a switch closed or opened to complete or interrupt a circuit through said source and said electro-magnet, and means actuated by said spring to close and open said switch respectively during and after said period of rest, 40 whereby said permanent magnet is swung down during said period of rest.

7. In combination with a movable time-indicating element, an oscillating element, 45 means whereby said oscillating element moves said time-indicating element, a spring alternately moved by and moving said oscillating element and having a period of substantial rest, and comprising a magnetic part, 50 a permanent magnet having a movement to and from a position in which it can appreciably attract said magnetic part, an electro-magnet attracting said permanent magnet from said position during said period of rest, means to return said permanent magnet to said position when said attraction of said electro-magnet is stopped, an electric-current source, a switch closed or opened to complete or interrupt a circuit through said 55 source and said electro-magnet, and means actuated by said spring to close and open said switch respectively during and after said period of rest, whereby said permanent magnet is attracted from said position during said period of rest of said spring.

8. In combination with a movable time-indicating element, a permanent magnet, means whereby said permanent magnet causes movement of said element, and means for adjusting the position of said permanent 70 magnet.

9. In combination with a movable time-indicating element, an oscillating element, a spring moving said oscillating element, means whereby said oscillating element 75 moves said time-indicating element, a permanent magnet, means whereby said permanent magnet causes movement of said spring, and means for adjusting the relation of said spring to said oscillating element. 80

10. In combination with a movable time-indicating element, an oscillating element, a spring moving said oscillating element, means whereby said oscillating element 85 moves said time-indicating element, a permanent magnet, means whereby said permanent magnet causes movement of said spring, means for adjusting the relation of said spring to said oscillating element, and 90 means for adjusting the position of said permanent magnet.

11. In combination with a movable time-indicating element, driving means having periods of substantial rest but driving said 95 element between said periods, a permanent magnet, and means whereby said permanent magnet occupies a position to actuate said driving means but moves from said position during said periods of rest. 100

12. In combination with a movable time-indicating element, an oscillating element, a spring, a connection between said spring and said oscillating element for moving said oscillating element, means whereby said 105 oscillating element moves said time-indicating element, a permanent magnet, means whereby said permanent magnet causes movement of said spring, and means for adjusting the effective length of said connection between said spring and said oscillating element. 110

13. In combination with a movable time-indicating element an oscillating element, a spring, a shaft turning with said oscillating element, a flexible connection to said spring, wound on said shaft for moving said oscillating element, means whereby said oscillating element moves said time-indicating element, a permanent magnet, means 115 whereby said permanent magnet causes movement of said spring, and means on said spring for winding up part of said connection to vary the effective length thereof. 120

14. In combination with a movable time-indicating element, an oscillating element, engaging means eccentric on said oscillating element, a lever, a fork on said lever, receiving said engaging means during a part of the oscillation of said oscillating ele- 125 130

ment in each direction, but releasing said engaging means during the remainder of each oscillation in each direction, whereby said oscillating element oscillates said lever in both directions once during each two oscillations of said oscillating element in both directions, means whereby said lever moves said time-indicating element, a permanent magnet, and means whereby said permanent magnet causes movement of said oscillating element.

15. In combination with a movable time-indicating element, an oscillating element, engaging means eccentric on said oscillating element, a lever, a fork on said lever, receiving said engaging means during a part of the oscillation of said oscillating element in each direction, but releasing said engaging means during the remainder of each oscillation in each direction, whereby said oscillating element oscillates said lever in both directions once during each two oscillations of said oscillating element in both directions, means whereby said lever moves said time-indicating element, and means for causing oscillation of said oscillating element.

16. In combination with a movable time-indicating element, a balance wheel, a shaft on said wheel, a support for said wheel and shaft, an elongated spring bent with a lower member and an upper member under said shaft and having the junction of said members at one side of said shaft, a support for said lower member, a connection from said upper member to said shaft whereby said spring has alternate periods of being flexed by said balance wheel and driving said balance wheel and a period of substantial rest between said alternate periods, a permanent magnet fulcrumed at once side of said shaft to tilt up and down, and having a pole between said spring members, said upper member comprising means whereby it is appreciably attracted by said pole when said magnet tilts said pole upward but not appreciably attracted thereby when said magnet tilts said pole downward, an electro-magnet beyond the fulcrum of said permanent magnet from said pole, tilting said pole downward when energized, an electric-current source, a switch in circuit with said source and said electro-magnet, means connected with said spring to actuate said switch for energizing said electro-magnet soon after

the beginning of each rest period of said spring and deenergizing said electro-magnet near the beginning of each driving period of said spring, and means whereby said balance wheel moves said time-indicating element.

17. In combination with a movable time-indicating element, mechanism for driving said element intermittently, with rest periods in the intermissions between driving periods, a permanent magnet to supply a driving impulse in each driving period, and electro-magnetic means to displace said permanent magnet relatively to said mechanism in each rest period.

18. In combination with a movable time-indicating element, a source of kinetic energy, a permanent magnet acted upon by said source to convert said kinetic energy into potential energy of its field, and mechanism for converting said potential energy into kinetic energy driving said time-indicating element, whereby said kinetic energy of said source may vary but its variation is substantially nullified in its conversion through the substantially constant field strength of said permanent magnet.

19. In combination with an element to be moved at a substantially uniform rate, an energy source, means acted upon by said energy source to store the kinetic energy of said action potentially, and mechanism for converting said stored potential energy into kinetic energy driving said element, said mechanism having an intermittent operation whereby variations of the kinetic energy of said source are substantially nullified in the conversion of said energy into potential and then again into the ultimate kinetic driving energy.

20. In combination with an element to be driven at a substantially uniform rate, mechanism for imparting uniform intermittent motions to said element, with rest periods in the intermissions between driving periods, means to store energy potentially during the rest periods and apply said energy kinetically to said mechanism during driving periods, and means to supply the energy to be stored, variation in rate of this supply being substantially nullified in the application to said mechanism by its passage through its potential condition during said rest periods.

WILLIAM A. HICKS.
